UNITED STATES PATENT OFFICE.

HARRY L. HURFF, OF PEORIA, ILLINOIS.

GAGE ATTACHMENT FOR WOODWORKING-MACHINES.

1,342,218.

Specification of Letters Patent.

Patented June 1, 1920.

Application filed March 12, 1918. Serial No. 221,971.

To all whom it may concern:

Be it known that I, HARRY L. HURFF, a citizen of the United States, a resident of Peoria, in the county of Peoria and State of Illinois, have invented new and useful Improvements in Gage Attachments for Woodworking-Machines, of which the following is a specification.

My invention relates to improvements in indicating means for wood working machines, and the principal object is the provision of means whereby the position of the wood working devices relative to the frame of the machine and relative to each other, are indicated coincident with their adjustments.

A further object of this invention is the provision of means on a wood working machine having a plurality of wood working devices, of indicating the adjustment of the devices relative to the frame of the machine and relative to each other, this latter including the distance between them and their relative vertical position.

Another object of this invention is the provision in combination with a plurality of cutters of a tenoning machine, of indicating means for indicating the depth of the lower shoulder of the tenon, the thickness of the tenon and the distance one cutter is offset from the other.

To the accomplishment of the foregoing and such other objects as may hereinafter appear, my invention consists in the combination, construction and arrangement of parts hereinafter described and then sought to be defined in the appended claims, reference being had to the accompanying drawings forming a part hereof, and which show merely for the purpose of illustrative disclosure, a preferred embodiment of my invention, it being understood that various changes may be made in practice within the scope of the claims without digressing from my inventive idea.

In the drawings,

Figure 1 is a front elevation of the upper part of a wood working machine, such as a tenoning machine, shown somewhat diagrammatically, with a mechanism constructed to embody my invention, applied thereto;

Fig. 2 is a side elevation of the left hand side of the mechanism shown in Fig. 1;

Fig. 3 is a side elevation on an enlarged scale of the various parts comprising one embodiment of my invention;

Fig. 4 is a front elevation of the same part shown in Fig. 3; the method of attachment to the frame of the wood working machine being indicated in dotted lines;

60

Fig. 5 is smaller detailed view in front elevation of the indicator shown set substantially at 0 (zero);

Fig. 6 is a horizontal transverse section taken substantially on line 6—6 of Fig 3; 65

Fig. 7 is a front elevation of a different embodiment of my invention, for the purpose of multiplying the indication so as to make the reading of the indicator easy;

Fig. 8 is a detailed view of a tenon that has been cut, showing the various measurements that are indicated by my invention.

In wood working machines and particularly tenoning machines at present in use, in order to obtain the proper thickness of the tenon and also the proper depth of the end shoulder, and also the proper alinement between the shoulders or the off-set relation therebetween, if that is desired, it is necessary to run an experimental piece of stock through the machine. It is obvious that this method of adjustment is inefficient and inconvenient to say the least, and therefore, I have provided in connection with the tenoning machine, indicating means which will indicate the thickness of the tenon, the depth of the lower shoulder, and the position of the cutters relative to each other, this indicating means being capable of being readily attached to existing types of machines with a minimum amount of trouble and expense.

Referring now to the drawings, in which I have illustrated in a more or less fragmentary and diagrammatic manner one type of tenoning machine, the numeral 1 designates the main frame of the machine, having the upper portion 2 and the carriage 3 which supports and moves the stock. This form of machine utilizes two cutters, the upper one being designated 4 and the lower one 5. The head stock 6 of cutter 4 is adjustable vertically in upper part 2 of the frame by means of the adjustable screw construction 7, while the head stock 8 for cutter 5 is adjustable in the part 2, by means of the adjustable screw construction 9.

The head stock 6 for the upper cutter 4 is also adjustable laterally or horizontally relative to the frame of the machine by means of the screw construction 10. By

means of these various adjustments, the height of the shoulder A (Fig. 8) is determined, the thickness of the tenon B is determined and the amount of off-set C between the upper and lower cutters, is determined. This mechanism, operation and means and manner of adjustment are embodied in machines at present on the market and in use, but as stated above, these machines have no manner of indicating the various adjustments referred to as A, B and C (Fig. 8) and the correctness of the adjustment can only be determined by the "cut and try method."

15 Referring now particularly to Figs. 3, 4, 5 and 6, in which I show one embodiment of my invention, the elongated gage bar 11, which is preferably formed of angle iron, as best seen in Fig. 6, is secured to the head stock 8 of the lower cutter 5 by securing means passing through the elongated slots 12. This gage bar 11 is provided on part 20 of its outer face with the scale 13 reading both ways from a fixed point, which I have marked 0 (zero). This manner of marking is, of course, arbitrary. Embracing this gage bar 11 and slidably thereon, is the indicating member 14 which is secured to the head stock 6 of the upper cutter 4 by means 25 of the bolt 15 and is provided with the opening or aperture 16, and has one end of this aperture provided with the notch or recess 17 which corresponds with one half of the 0 (zero) marking on the scale 13. The indicating bar 18 is secured as at 19, to the upper part 2 of the machine and has its indicating portion extending across in front of the opening 16 in the member 14, and the scale 13 on the member 11, being provided with the notch or recess 20 corresponding substantially with the lower half of the 0 (zero) marking and adapted to co-operate at 0 (zero) adjustment with the notch or recess 17 in the member 14 to form 30 a 0 (zero). It is to be recalled that the gage bar 11 is connected to the head stock 8 of the lower cutter and, of course, movable therewith, and that the indicating member 14 is connected to the head stock 6 of the upper cutter and movable therewith. Therefore, the position of the gage bar 11 and indicating member 14 relative to each other, will indicate the relative position between the two cutters and also in view of the fact 35 that the indicating member or arm 18 is secured to the upper part 2 of the main frame of the machine, the position of the scale of the gage bar 11 relative to this indicating arm member 18 will indicate the relative position of the lower cutter to the frame, and therefore the depth of the shoulder A (Fig. 8), the relative position between the cutters indicating the thickness of the tenon B (Fig. 8).

In order to indicate the position of the upper cutter 4 laterally with respect to the lower cutter 5, I secure to the head stock thereof, preferably by means of the bolt 15, the indicating scale 21 and on the laterally movable carriage 22 therefor, the indicating pointer or finger 23. I provide this scale preferably with the 0 (zero) marking, which indicates that the cutters 4 and 5 are in exact vertical alinement and, therefore, the finger or pointer 23 will indicate on the scale 21 any variation in its relative vertical alinement.

It is seen, therefore, that I have provided a very simple construction for indicating co-incidently with any adjustment, the position of the lower cutter with respect to the frame or carriage of the machine, and thereby indicate the depth of the cut or shoulder A (Fig. 8), and also the distance between the upper cutter and the lower cutter which determines the thickness of the tenon B (Fig. 8), and also the position of the two cutters relative to each other as indicated by the off-set distance C (Fig. 8).

We will assume for the purpose of example, that the indicating means are in the adjustments shown in Fig. 5, which is substantially 0 (zero). This means that the cutters are as close together as they can be adjusted and practically on a line with the top of the carriage, and therefore, the bottom line of the stock. It is desired to cut a tenon having a lower shoulder of the depth A (Fig. 8), the upper cutter having been moved out of the way the lower cutter is moved upwardly, which, of course, moves the gage bar 11 and accordingly moves the 0 (zero) point on the scale 13 thereof upwardly from the indicating bar 18. When the distance between the 0 (zero) mark on the scale and the indicating bar or member 18 equals the distance A, the operator knows that that adjustment is complete and correct.

Assuming further that the tenon is to be cut of a thickness B (Fig. 8), the operator moves the head stock and upper cutter 4 in the proper direction, which, of course, moves the member 14 until the distance between the 0 (zero) mark on the scale 13 and the indicating notch 17 on the upper edge of the opening 16 into the member 14 corresponds to the distance B (Fig. 8), when the operator knows that this adjustment is complete and correct. The adjustment is now complete if it is desired to cut the upper and lower shoulders of the tenon in vertical alinement, but if one is to be off-set from the other, the operator moves the upper head stock to the right by means of the screw connection 10 until the pointer or finger 23 indicates on the scale 21, the distance C (Fig. 8), when he knows that this adjustment is complete and proper. The

work can then be run through the machine without the necessity of further adjustment or experimenting.

In order to make the indications plainly readable, it is advisable at times to provide a scale or indicator in which the indications are multiplied, and I provide this by the mechanism shown in Fig. 7. The arc shaped scale 24 is secured to the stationary frame 10 of the machine. The one pointer 25 is connected to the head stock for the upper cutter 4 and the other pointer 26 is connected to the head stock of the lower cutter. The same operation and adjustment of the cutters will produce the indication on the scale, the same as in the mechanism previously described, with the exception that the indication will be some predetermined multiple of the dimensions, as determined, of course, 20 by the leverage of the pointers.

While I have described this invention and shown it applied to tenoning machines, it is obvious that it may be capable of use with other types of devices, wherein the same adjustments and working conditions are met, and that my invention is not to be limited 25 to this disclosure, except as by the scope of the following claims.

What I claim is:

30 1. An indicating means including in combination, an elongated bar member adapted to be connected to a vertically movable element to move therewith, said bar member having an indicating scale provided on one face thereof, another member coöperating with said bar member and moving over the indicating scale thereon and having an opening therein with one edge of said opening adapted to coöperate with said scale to indicate, said 35 other member being adapted to be connected to another vertically movable element to move therewith, whereby the relative position of the two movable elements is indicated and a third member adapted to be connected to stationary means and to coöperate with said scale and said other member so that when the bar member and said other member are moved for adjusting purposes their relative position to a permanent 40 stationary position will be indicated.

45 2. An indicating means, including, in combination, a bar member adapted to be connected to a vertically moving element to move therewith, said bar member having a scale, another member coöperating with said bar member and the scale thereon to indicate, said other member being adapted to be connected to another vertically moving element to move therewith whereby the relative 50 position of the two movable elements is indicated, and a third member adapted to be connected to the stationary means with which the scale and said other member coöperate for indicating purposes.

3. An indicating means, including, in combination, a bar member adapted to be connected to a vertically moving element to move therewith, said bar member having a scale, another member coöperating with said bar member and the scale thereon to indicate, said other member being adapted to be connected to another vertically moving element to move therewith whereby the relative position of the two movable elements is indicated, and a third member adapted to be connected to the stationary means with which the scale and said other member coöperate for indicating purposes, and a two-part indicating means adapted to be connected with one of said vertically movable means so as to indicate its relative horizontal displacement.

4. An indicating means for a tenoning machine having a main frame, a plurality of head stocks vertically adjustable in said main frame, a cutter mounted in each head stock and means for adjusting one of said cutters laterally with respect to the other, said indicating means including, in combination, an indicating member adapted to be connected to each head stock and to move vertically therewith and to coöperate to indicate the relative position of the cutters to each other, and another indicating member adapted to be secured to the frame of the machine so as to coöperate with said first-mentioned indicating members to indicate the relative position of the cutters to the frame of the machine.

5. An indicating means for a tenoning machine having a main frame, a plurality of head stocks vertically adjustable in said main frame, a cutter mounted in each head stock and means for adjusting one of said cutters laterally with respect to the other, 100 said indicating means including, in combination, an indicating bar adapted to be secured to the lower head stock and having a scale provided thereon, an indicating member adapted to be secured to the upper 105 head stock to move therewith and to coöperate with said scale so as to indicate the relative distance between the two cutters, and a stationary indicating means adapted to be secured to the frame to coöperate with 110 said indicating bar to indicate the position of the lower cutter relative to the frame.

6. An indicating means for a tenoning machine having a main frame, a plurality of head stocks vertically adjustable in said main frame, a cutter mounted in each head stock and means for adjusting one of said cutters laterally with respect to the other, said indicating means including, in combination, an indicating member adapted to be connected to each head stock and to move vertically therewith and to coöperate to indicate the relative position of the cutters to

each other, and another indicating member adapted to be secured to the frame of the machine so as to coöperate with said first-mentioned indicating members to indicate the relative position of the cutters to the frame of the machine, and a two-part indicating mechanism mounted on the head

stock of said laterally adjustable cutter to indicate the lateral displacement of said cutter in reference to the frame.

10

In witness whereof, I have hereunto affixed my hand this 9th day of March, 1918.

HARRY L. HURFF.
